UNITED STATES PATENT OFFICE.

HIRAM PERCY MAXIM AND HERBERT W. ALDEN, OF HARTFORD, CONNECTICUT, ASSIGNORS TO THE COLUMBIA AND ELECTRIC VEHICLE COMPANY, OF SAME PLACE AND JERSEY CITY, NEW JERSEY.

DESIGN FOR A VEHICLE-AXLE.

SPECIFICATION forming part of Design No. 32,179, dated January 30, 1900.

Application filed November 17, 1899. Serial No. 737,375. Term of patent 14 years.

To all whom it may concern:

Be it known that we, HIRAM PERCY MAXIM and HERBERT W. ALDEN, citizens of the United States, and residents of the city of Hartford, county of Hartford, State of Connecticut, have invented and produced a certain new and original Design for a Vehicle-Axle, of which the following is a specification, reference being had to the accompanying drawings, forming a part hereof.

This invention relates to the axles of motor-vehicles and the like which support the steering-wheels, usually the front axles; and it consists in the design therefor shown in the accompanying drawings, in which—

Figure 1 is a front elevation of an axle which embodies the design, and Fig. 2 is a plan view thereof.

The design is particularly concerned with the end portions of the axle, the middle or main portion *a* being substantially straight.

At each end is a fork or yoke formed by a generally-upright member *b* and two nearly-horizontal projecting members *c*, the alignment of these two members being oblique to the axis 25 of the portion *a*. From the upper part of the yoke a portion *d* is extended inwardly and upwardly.

The essential feature of the design is the portion extended inwardly and upwardly 30 from the upper part of the yoke at each end of the axle.

We claim as our invention—

The design for a vehicle-axle, substantially as shown and described.

This specification signed and witnessed this 35 12th day of November, A. D. 1899.

HIRAM PERCY MAXIM.
HERBERT W. ALDEN.

In presence of—

A. F. BARDWELL,
HERMANN F. CUNTZ.
